UNITED STATES PATENT OFFICE.

DANIEL J. DALY, OF BOSTON, MASSACHUSETTS.

COUPLING FOR MEMBERS FOR BUILDING-FRAMES, &c.

949,394.

Specification of Letters Patent. Patented Feb. 15, 1910.

Application filed October 6, 1909. Serial No. 521,393.

To all whom it may concern:

Be it known that I, DANIEL J. DALY, of Boston, in the county of Suffolk and State of Massachusetts, have invented certain new and useful Improvements in Couplings for Members of Building-Frames, &c., of which the following is a specification.

This invention has for its object to provide means for connecting the adjacent ends 10 of two alined uprights constituting members of the frame work of a building, and for connecting with said uprights the ends of horizontal frame members.

My invention is intended particularly for 15 connecting upright and horizontal frame members which constitute the supports of piazza floors in apartment buildings, where each story above the first has a piazza, the floor of which constitutes the roof of the 20 piazza below it.

The invention is intended to enable the upright frame members or supports to be conveniently coupled together end to end in such manner that they may be readily 25 assembled and separated by horizontal side-wise movements, and to enable the horizontal members which support the piazza floor boards to be readily connected to the upright members or supports.

30 The invention consists in the improvements which I will now proceed to describe and claim.

Of the accompanying drawings, forming 35 a part of this specification,—Figure 1 represents a perspective view of a frame coupling embodying my invention, and portions of two upright and horizontal frame members engaged therewith. Fig. 2 represents a top plan view of the coupling shown in 40 Fig. 1. Figs. 3 and 4 represent, respectively, a perspective view and an end view of a modification of my invention. Figs. 5 and 6 represent, respectively, a perspective view and an end view of another modification.

45 The same reference characters indicate the same parts in all the figures.

In carrying out my invention, I provide a frame coupling composed of three sides 10, 11, and 12, the sides 11 and 12 being 50 at right angles with the side 10, and all cast in a single piece. The coupling thus formed is open at one side to permit the lateral or horizontal insertion of alined upright frame members 13 and 14. The in-

terior of the structure formed by the sides 55 10, 11, and 12 is provided with a transverse partition 15 located midway between the ends of the coupling, and forming a stop for the ends of the frame members 13 and 14. The sides 11 and 12 are provided with 60 holes for the reception of attaching screws 16. It will be seen that the sides 10, 11, and 12 and the partition 15 collectively form two alined sockets, and that the frame members 13 and 14 may be assembled by 65 simply slipping said members laterally into the sockets, one below and the other above the partition 15.

The described coupling is provided with 70 lateral three-sided branches 17, for the reception of horizontal frame members 18, these being, for example, the sills or timbers which support the floor or roof boards. The branches 17 are cast integrally with the 75 sides of the main coupling, and may be 80 formed on the sides 11 and 12, as shown in Figs. 1 and 2; or on the sides 10, 11, and 12, as shown in Figs. 3 and 4; or on the sides 10 and 12, as shown in Figs. 5 and 6, according to the location of the coupling. 85

The open side of the main coupling is in all cases arranged to face the exterior of the building, so that the upright frame members may be inserted and removed 90 without interference with the floor or roof 85 boards supported by the horizontal members.

The construction shown in Fig. 1 is intended for application to a center post. The construction shown in Fig. 3 is intended 90 for a center post which is adapted to support three horizontal frame members. The construction shown in Fig. 5 is intended for a corner post.

It is obvious that the frame members 18 95 may be piazza railings located above the floor instead of being supports for floor boards.

In each embodiment of the invention the vertical sides of the arm or branch 17 are 100 provided with holes for the reception of attaching screws.

I claim:

A three-sided frame coupling having a transverse partition, forming, with the three 105 sides of said coupling, two alined sockets adapted to receive two alined upright frame members, and open at one side of the

coupling whereby said frame members may be inserted and removed by sidewise movements, the said coupling having three-sided branches projecting from its closed sides, 5 each branch and the side of the coupling from which it projects forming a socket for a horizontal frame member.

In testimony whereof I have affixed my signature, in presence of two witnesses.

DANIEL J. DALY.
